UNITED STATES PATENT OFFICE.

KARL K. NIELSEN, OF CHICAGO, ILLINOIS.

CONNECTER FOR HEATING APPLIANCES.

Application filed January 27, 1922. Serial No. 532,081.

To all whom it may concern:

Be it known that I, KARL K. NIELSEN, citizen of the United States, residing at Chicago, in the county of Cook and State 5 of Illinois, have invented certain new and useful Improvements in a Connecter for Heating Appliances; and I do hereby declare the following to be a full, clear, and exact description of the invention such as 10 will enable others skilled in the art to which it appertains to make and use the same.

My invention relates to electrical connectors of the socketing type adapted for use in affording electrical connections to 15 pins or plugs forming circuit terminals. Connecters of this general type are commonly used for making the electrical connections to electric heating devices having terminals in the form of projecting pins or 20 studs. In practice, the pins or studs as employed on different makes and types of such devices are not uniform in size even if substantially cylindrical in the shape of their contacting portions, and on some makes of 25 electric heating devices are flat instead of round. For this reason, the so-called attaching plugs or connecters as commonly sold in connection with flexible cords for carrying the current to such heating 30 devices will not properly fit these devices interchangeably.

Moreover, while it is customary to some extent to provide such connecters with 35 spring arrangements to make the contact clips adapt themselves to variations in the size of the interposed pin or stud, the adjustment thus provided commonly reduces the extent of contact to a small portion of the length of the interposed pin or stud. 40 Consequently, instead of having this pin firmly clamped between a pair of clips engaging the pin for a considerably length, the engagement is so short that it permits the detachable connecter to rock on the pin 45 and affords such a limited contact as to cause a sparking or arcing. This arcing is increased when a strain on the connecter causes a rocking of the latter and soon roughens the surface of both the pin and 50 connector clip, thereby further decreasing the firmness and carrying capacity of the electrical connection for which the detachable plug or connecter is employed.

My invention aims to avoid these diffi- 55 culties and to provide a connecter of the above described type in which each pair

of the associated clips is so mounted that the clips comprising that pair can rock with respect to each other so as to engage an interposed pin or stud for a considerable length thereof and so that this engagement along a considerable contact area can readily be secured with round pins varying considerably in size and even with flat studs. It also aims to provide spring means 60 associated with each pair of contact clips (and desirably integral with the said clips) for forcing the clips towards each other and into the said ample contacting disposition, and preferably aims to dispose the said 65 spring means where they will most advantageously accomplish the desired purpose. Furthermore, my invention aims to provide such contact clips in a simple and inexpensive construction and one which can 70 readily be employed in connection with the two-part insulating casings or bodies as commonly employed for such connecters. It also aims to arrange the parts so that the desired action of the spring means will 75 be secured automatically and without requiring either particular care in the assembling of the parts or a knowledge of the size or type of connecter pins with which 80 the connecter is to be used.

Still further and also more detailed objects of my invention will appear from the following specification and from the accompanying drawings, in which

Fig. 1 is a plan view of a twin terminal 90 connecter embodying my invention, with a portion of the casing broken away to show the position of one pair of the clips.

Fig. 2 is an enlarged transverse section taken along the line 2—2 of Fig. 1.

Fig. 3 is a fragmentary transverse section taken along the line 3—3 of Fig. 2 and showing the connecter as used in connection with a substantially cylindrical terminal stud or pin.

Fig. 4 is a similar section showing the same connecter as used with a flat terminal stud.

Fig. 5 is a transverse section through one pair of the connecter clips, taken along the 105 line 5—5 of Fig. 2.

Fig. 6 is a plan view of the lower clip of Figs. 2, 3 and 4.

Fig. 7 is a bottom view of the upper clip 110 of the same figures.

Fig. 8 is a section similar to the forward portion of Fig. 2 and showing another

spring arrangement suitable for use in embodying my invention.

In accomplishing the purposes of my invention after the manner of the accompanying drawings, I provide the usual insulating casing 1 made of a rubber composition or the like in two parts normally secured to each other by bolts 2 and cooperating to provide a pair of parallel bores 3 both opening at the forward end of the casing and both leading to a single bore 4 at the rear end of the casing through the wires 5 lead out to the source of current.

Disposed within each of the bores 3 is a pair of contact clips, one of which is connected to a wire 5 by a screw 6 while the other has portions slidably engaging the aforesaid clip but is not directly connected to the circuit wire. In the embodiment of Figs. 1 and 2, the wire connection is made to the upper clip 7 by a screw 6 threaded into the same and this clip has at its edges a pair of notches 8 forming guides for up-standing guide fingers 9 on the corresponding lower clip 10. Each of the two clips has a contacting part consisting of a concave portion 11 which desirably corresponds in form for the major portion of its length to a portion of a cylindrical tube having its forward end flared out, and which desirably has longitudinal border strips 12 at its opposite edges, these border strips 12 being disposed in the same plane with each other. The portions 11 on the two clips comprising each pair of contact members have their concave faces directed towards each other, so that these faces may simultaneously engage opposite sides of the terminal pin 13 to which the circuit connection is to be made from the wire 5.

To insure a firm contacting of these portions 11 with the pin 13. I provide spring means for simultaneously urging the same towards each other and against the interposed pin, and I desirably make these spring means integral with the clips 7 and 10. For this purpose I am here showing each clip as provided at its opposite edges with spring fingers 14 which are bowed away from each other and away from the axis of the bore 3 housing the clip, and which fingers are continuously forced by their resiliency against the upper and lower walls of the bore 3 of the insulating casing so that they tend to force these clips closely towards each other when no terminal pin or stud is inserted between them. When such a terminal pin is inserted by slidably introducing the same (as permitted by the flaring mouth ends of the contact portions 11), the spring fingers force the said contact portions 11 tightly against opposite sides of the terminal pin. In doing so, the engagement of the insulator bore walls with the convex faces of the spring fingers 14

allows the pair of clips to rock about their said engagement with the said walls of the bore housing the same, so that they can automatically adjust themselves to cause the said contact portions 11 to engage a considerable portion of the length of the interposed terminal pin. I therefore secure long contacting surfaces which are automatically adjusted according to variations in the diameter of the interposed terminal pin and which grip the latter for such a length as to avoid any rocking of the contact clips with respect to the terminal pin. By so doing, I avoid the arcing and pitting of either the pin or the clips even when the same connector is used interchangeably with current-consuming devices having terminal pins which vary considerably in diameter.

Moreover, by providing each of the clips with border strips 12 as above described, I am able to use the same connector clips also with current consuming devices employing flat terminal studs such as the stud 15 of Fig. 4, as the border strips 12 will bear flatwise against the opposite edge portions of such a flat stud 15 so as to clamp the latter firmly. So also, the yielding of the spring fingers 14 permits each pair of connector clips to tilt or move somewhat in any desired direction, so that the clips will automatically adjust themselves to little variations in the spacing of a pair of terminal pins or studs on any appliance, or to a departure from an exact parallel position of such pins. My construction therefore enables me to provide a detachable connector which can be used interchangeably with current-consuming devices varying widely in the sizes of their terminals, while assuring an ample and firm electric contact in every case. To facilitate the automatic adjusting of the contacting clip portions to the size and shape of the interposed pin, I desirably arrange the spring fingers 14 so that the bearing of the same against the walls of the bore 3 housing the clip will be approximately opposite the middle of the length of the clip portions which engage the interposed terminal pin or stud, after the manner shown in Fig. 2.

However, while I have illustrated and described my invention in an embodiment including guide fingers 9 on one of the clips and including a pair of spring fingers 14 integral with each of the clips, I do not wish to be limited to these or other details of the construction and arrangement thus disclosed, as it will be obvious that many changes might be made without departing either from the spirit of my invention or from the appended claims. For example, instead of using spring fingers integral with the clips and engaging the opposite walls of the bore housing the same, I may employ a separately formed clip 16, formed from a

single piece of wire after the manner of a paper clip and having at its free ends a pair of arms 17 and 18 respectively engaging the outer faces of the contact parts 11 on the two clips and continuously tending to force these towards each other. With either embodiment, it will be obvious that each pair of clips is to a certain extent floatingly supported in the insulator bore housing the same and has freedom for adjusting itself to the size, shape and position of the terminal pin with which it is to be used. Consequently, no particular care needs to be exercised in using such connectors, as the wireman merely opens the casing by removing the bolts 2, connects each wire to one of the clips by the screw 6 threaded thereon and again closes the insulating casing.

I claim as my invention:—

20 1. A connector of the type described including an insulating casing, a wire terminal clip in the casing composed of two parts formed to engage opposite sides of a pin, one of said parts having a pair of 25 notches formed in its side edge and the other part having a pair of guide fingers freely received in the notches, and formed so as to permit either part to have rocking movement throughout its length independent of the other part, means to connect a wire to one of the parts, and spring means for each of the parts interposed between same and the casing to form bearings intermediate the lengths of the parts about which 30 bearings the parts may independently rock.

25 2. A connector of the type described including an insulating casing, a wire terminal clip in the casing composed of two

parts formed to engage opposite sides of a pin, means for mounting the parts whereby to permit each part to have rocking movement throughout its length independent of the other part, means to connect a wire to one of the parts, and spring means for each of the parts interposed between same and the casing to form bearings intermediate the lengths of the parts about which 40 bearings the parts may independently rock. 45

3. A connector of the type described including an insulating casing, a wire terminal clip in the casing composed of two parts formed to engage opposite sides of a pin, means to connect the parts to permit each to have rocking movement throughout its length independent of the other, means to connect a wire to one of the parts, and means to mount the parts to cause same to closely engage the pin and to enable each of the parts to have independent rocking movements. 50

4. A connector of the type described including a chambered insulating casing, a wire terminal clip in the chamber composed of two parts, formed centrally of their widths to engage opposite sides of a pin, each part having a pair of spring fingers located on the respective opposite sides of the central portion, said fingers having their outer side edges in engagement with opposed walls of the chambers, the fingers having bowed portions engaging other opposed walls of the casing. 55 60 65 70

Signed at Chicago, Illinois, Jan. 24th, 1922.
